UNITED STATES PATENT OFFICE.

ALBERT E. WHITE, OF ROCKFORD, ILLINOIS.

IMPROVED BOOT-BLACKING MACHINE

Specification forming part of Letters Patent No. 42,707, dated May 10, 1864.

To all whom it may concern:

Be it known that I, ALBERT E. WHITE, of Rockford, in the county of Winnebago and State of Illinois, have invented a new and Improved Device for Blacking and Polishing Boots and Shoes; and I do hereby declare that the following is a full, clear, and exact description thereof, which will enable any person skilled in the art to make and use the same, reference being had to the accompanying drawings, making a part of this specification, in which—

Figure 1 is a side sectional view of my invention, taken in the line x x , Fig. 2; Fig. 2, a transverse vertical section of the same, taken in the line y y , Fig. 1.

Similar letters of reference indicate corresponding parts in the two figures.

The object of this invention is to obtain a simple device by which boots and shoes may be blackened and polished far more expeditiously than it can be done by hand.

To this end the invention consists in the employment or use of two rotary brushes placed in a suitable frame and arranged and operated substantially as hereinafter shown and described.

A, represents a base plate, on which two uprights, B B', are secured, the latter, B', being much higher than the former, B. C is a horizontal shaft, which has its bearings in the uprights B, B', and is allowed to turn freely therein. On this shaft there is firmly keyed a brush-wheel, D, the periphery of which is of concave form, as shown clearly in Fig. 1, and there is also placed loosely on the shaft a tube, E, which passes through the upright B', and has a pulley, F, upon it. On this tube E there is secured a brush wheel, G, which is precisely similar to the brush-wheel D, as shown in Fig. 1. The shaft C projects some distance beyond the tube E, and has upon it a small friction-wheel, H, with which a large wheel, I runs in contact. This wheel I has its axis a in the upright B', and to the

inner side of I there is attached concentrically a pulley, J, smaller in diameter than I, and around which a belt, K, passes.

The brush-wheel G rotates with less speed than the brush-wheel D, and the former is designed for applying the blacking to the boot or shoe, while the latter is used for polishing the same. The two brush-wheels rotate in opposite directions, according to the arrangement of the driving mechanism herein shown and described, but that is not an essential feature, and therefore the belt K may be crossed, if desired, and both brush-wheels made to rotate in the same direction. The blacking may be applied to the brush-wheel G by means of a hand-brush or other means, and the wheel I, being rotated by hand, the brush-wheel G applies the blacking to the boot or shoe, the latter being on the foot and held underneath and over the brush-wheel, as shown in Fig. 2 in dotted and solid red outline. When the boot or shoe is properly blackened, it is applied to the brush-wheel D, which, on account of its quick rotation, speedily polishes it.

Although the difference of the direction in which the two brush-wheels rotate is not essential, the difference in speed is important, for if the brush-wheel G were made to rotate as rapidly as is necessary for the polishing brush-wheel D, it would be liable to throw the blacking upon the person.

Having thus described my invention, what I claim as new, and desire to secure by Letters Patent, is—

A boot and shoe polishing machine composed of two brush-wheels, D G, arranged to revolve relatively with different degrees of speed, in the manner substantially as herein shown and described.

A. E. WHITE.
